UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

MULTIPLE-TUCK FOLDER FOR SEWING-MACHINES.

1,263,870.

Specification of Letters Patent.

Patented Apr. 23, 1918.

Application filed May 23, 1916. Serial No. 99,380.

To all whom it may concern:

Be it known that I, ALBERT H. DE VOE, a citizen of the United States, residing at Westfield, in the county of Union and State of New Jersey, have invented certain new and useful Improvements in Multiple-Tuck Folders for Sewing-Machines, of which the following is a specification, reference being had therein to the accompanying drawings.

- 10 This invention relates to devices for producing tucks in fabrics, and is designed more particularly for producing series of standing tucks closely spaced and crowded together to form what is known as "mushroom" tucking, such as that disclosed in my Patent No. 1,164,790, of December 21, 1915; and it has for its primary object to provide tuck-forming means adapted to produce simultaneously a plurality of closely spaced standing tucks of uniform depth and spacing apart.

20 In its preferred embodiment, the tucking device is applied to a sewing machine equipped with stitch-forming mechanism including a plurality of laterally spaced reciprocating needles. The bed-plate has secured thereon a forming plate provided upon its upper face with a series of convergent tuck-forming ribs of progressively decreasing width and increasing depth merging at their delivery end portions in substantially parallel standing blades grouped in pairs whose extremities enter respectively the flaring mouths of grooves 30 formed in the lower face of the presser-foot. An upper forming plate is sustained for vertical movement upon a rigid support carried by the bracket-arm and has upon its under face a depending series of convergent forming ribs normally entering the spaces between the lower forming ribs, said plate being provided near its contracted forward end with an inspection aperture through which access may be had between the upper 40 forming ribs to the lower forming ribs for adjusting the work preparatory to a tuck-forming and stitching operation.

The component tuck-forming blades of each pair are preferably extended to and wholly at opposite sides of a needle in advance of which is disposed what may be termed a creasing blade which is sustained

by the presser-bar at a position intermediate the component forming blades of said pair.

As the tuck-forming blades or elements 55 of each pair have their delivery ends directed wholly to opposite sides of the needle-path, the tucks formed by such blades will not be penetrated by the needle.

Sustained by the support for the upper 60 forming plate is a series of elements which may be termed positioning blades sustained upon shanks depending between the pairs of forming blades, the positioning blades extending laterally intermediate adjacent 65 groups or pairs and beneath the component forming blades thereof and beyond the paths of movement of the needles of the respective pairs of forming blades. The positioning blades are preferably disposed at 70 different levels in marginally overlapped relation in such manner that they produce lateral folds in the body fabric at the bases of the adjacent standing tucks which are united by lines of stitching passing through 75 the creases between the component tucks of each pair and through such overlapped folds of the body fabric.

The invention will be understood by reference to the accompanying drawings, in 80 which Figure 1 is a front end view and Fig. 2 a plan of the forward portion of a sewing machine provided with a tucking device embodying the present improvement. Fig. 3 is a view of the lower face of the 85 upper forming plate, Fig. 4 a similar view of the upper face of the lower forming plate, and Fig. 5 is a transverse section taken through the upper and lower forming plates and showing in dotted lines the position of the material between the same. Fig. 6 is a perspective view showing the needles and presser-foot with the adjacent tuck-forming elements.

Fig. 7 is a front elevation of the parts 95 represented in Fig. 6 and Fig. 8 a plan of the same with a portion of the bed-plate. Fig. 9 is a bottom view of the presser-foot with the adjacent portion of the lower tuck-forming member. Fig. 10 is an end elevation of the tuck-forming elements and their supporting means, viewed from a position rearward of the needles. Figs. 11, 12 and 100 13 are perspective views of the positioning

and creasing elements, detached. Fig. 14 is an enlarged front end elevation representing in part the tuck-forming elements shown in Fig. 10, but indicating the position of the material in connection therewith.

The sewing machine represented in the accompanying drawings is of the well-known Singer multiple-needle single-chain-stitch type, comprising a frame constructed with the usual bed-plate 1, from which rises the hollow standard 2 sustaining the tubular overhanging arm 3 which terminates in the head 4. Within the bracket-arm head is journaled the reciprocating needle-bar 5 carrying the transverse multiple needle-clamp 6 provided with the laterally spaced eye-pointed needles 7 coöoperating in practice with oscillating loopers mounted upon the rock-shaft 8.

Journaled also in the head 4 is the presser-bar 9 provided with the usual thrust collar 10 between which and the bushing 11 is the surrounding spring 12. The presser-bar may be raised and lowered by means of the usual cam-lever 13 acting upon a suitable projection of the collar 10. To the reduced lower end of the presser-bar is secured the shank 14 of the presser-foot upon which is pivotally mounted the rocking foot-plate 15 which is provided in its under side with the narrow tuck-receiving grooves or channels 16 each directed toward one of the needles 7 having at its forward end a flaring mouth 17.

Opposed to the presser-foot is the feed-dog 18 carried by the feed-bar 19 which is suitably actuated by well-known means.

Secured upon the forward marginal portion of the bed-plate 1 by screws 20 entering the elongated apertures 21 is the lower forming plate 22 which is provided upon its upper face with a series of convergent tuck-forming ribs 23 of progressively decreasing width and increasing depth and merging at their delivery end portions in substantially parallel standing blades 24 extending within the direction of feed to and preferably slightly beyond the needle-paths.

These blades are represented as uniformly spaced at one-half the spacing of the needles from each other, but in the performance of their function they may be considered as arranged in groups each comprising a pair of which the component blades are directed wholly to opposite sides of the respective needles with their extremities entering the flaring mouths of the presser-foot groove 16, as represented particularly in Figs. 6 to 9 inclusive.

Overhanging the lower forming plate is the substantially triangular upper forming plate 25 which is constructed, like the lower forming plate, with a series of convergent tuck-forming ribs 26 of progressively decreasing width and increasing depth but ter-

minating at their forward ends adjacent the rearward extremities of the blades 24. The upper and lower tuck-forming ribs are disposed in interlocking relation, as represented in Fig. 5, so as to produce a series of crimps or folds in the body fabric as it advances between the plates 22 and 25 toward the stitch-forming mechanism. Near its forward end the body of the plate 25 is cut out to form a clearance aperture 25' through which are exposed the upper portions of the ribs 26 and the tops of the intermediate lower forming ribs 23, as represented particularly in Fig. 8.

To the top of the upper tuck-forming plate 25 is secured the foot 27 of a stand comprising two upright members 28 fitted within vertical slideways 29 in a block 30 at the outer end of an arm or support 31 rigidly secured to and projecting forwardly from the bracket-arm head. Journaled within suitable bearings of the block 30 is a rock-shaft 32 carrying at opposite ends the crank-disks 33 each provided with a stud-pin 34 entering the apertured upper end of a link 35 whose apertured lower end is entered by a stud-pin 36 tapped into one of the upright members 28. A lifting lever 37 secured upon the rock-shaft 32 provides a means for rocking the latter for raising and lowering the upper forming plate, as represented respectively in full and dotted lines in Fig. 1.

Owing to the great reduction in width of the fabric effected by the folding operation in its passage to the stitch-forming mechanism, it is desirable to effect the lateral drawing in of the fabric by a gradual process involving the employment of comparatively long upper and lower forming plates whose forming ribs should be rigidly maintained in fixed relation while permitting the inspection and manual advance of the work near the delivery end of the attachment. To this end, these plates are constructed to afford connections between their respective forming ribs at opposite ends thereof with an interruption of such connection intermediate the ends. As the two forming plates are sustained respectively by the bed-plate and the overhanging bracket-arm, ample space is provided on both sides of the attachment for the untucked material adjacent the tucked portion, thereby providing for operation upon wide pieces of fabric, which may be passed through the attachment repeatedly to form adjacent sections of tucking together aggregating the desired width in the finished article.

Entering the spaces between the tuck forming blades or elements of each pair, and disposed parallel therewith, is a series of creasing blades 38 each formed at the lower end of a shank 39 depending from the forward limb of a U-shaped carrier 40 whose shorter opposite limb terminates in a split

collar 41 which is clamped upon the presser-bar 9 above the presser-foot by means of the clamp-screw 42.

As indicated particularly in Fig. 7, the forming blades 24 are cut away upon the under side considerably above the level of the plate 22 to afford clearance for the positioning blades 43 each of which is directed within the line of feed and extends laterally beneath adjacent groups or pairs of forming blades with their opposite edges extending to or beyond alinement with adjacent needles 7. These positioning blades are formed at the lower edges and transversely of shanks 44 depending between the adjacent groups of forming blades and provided in their upper portions with enlargements 45 from which project upwardly the studs 46.

These studs 46 are adjustably secured by means of set-screws 47 in vertical sockets in a cross-member or carrier 48 at the lower end of a bar 49 rigidly secured to and depending from the supporting arm 31. The marginal portions of adjacent positioning blades are preferably disposed in overlapping relation, and are therefore arranged at different levels, as shown particularly in Figs. 10 and 14. The various fabric-engaging blades overhang the throat-plate, a portion 50 of which is flush with the top of the bed-plate and merges just in advance of the needle-apertures 52 therein into the upwardly offset surface 51 which is shown formed with the feed apertures 53.

The blades 38 and 43 terminate at their delivery ends adjacent the needle-paths, the lower series of positioning blades having their delivery extremities farther in front of the needle-holes than the upper series by reason of the curvature of the fillet between the upper and lower faces of the throat-plate, as represented in Figs. 7 and 8.

In the use of the apparatus, the material *m* (represented in dotted lines in Fig. 5) is introduced beneath the upper forming plate 25 when lifted to its elevated position as represented in dotted lines in Fig. 1, and the forming plate is lowered to enter the upper forming ribs 26 between the lower forming ribs 23 for the production of a series of closely spaced crimps. The material may be advanced toward the stitch-forming mechanism by the use of a stiletto for engagement of the material through the inspection aperture 25', the forward portion being thus directed beneath the crimping blades 38 and over and around the laterally extending positioning blades, as represented in Fig. 14.

The forward end of the fabric *m* having been extended into the range of action of the feed-dog, and the presser-foot lowered thereon, the machine is set in operation and the work is advanced through the various tuck-forming and positioning elements, each

needle entering a crease or depression *s* formed by its respective creasing blade 38 between the pairs of tucks *t* and penetrating successively the lateral folds *v* and *v'* in the body fabric formed by the positioning blades 43 at the bases of the pairs of standing tucks, as indicated in Fig. 14. As the work advances past the needles, the tucks *t*, which are guided with precision to the stitching point by reason of the extension of the blades 24 to and beyond the needle-paths, enter the flaring mouths of the clearance grooves 16 in the presser-foot in which they are crowded together so as to issue from beneath the presser-foot in uniform spacing.

The arrangement of the several elements of the apparatus shown in the drawings is designed for forming tucks in a single ply of fabric, in which case the bases of the tucks are required to be secured together to retain the tucks in position; but in case a backing is employed to which the tucks may be secured by lines of stitching, it is evident that the lateral folds in the body fabric need not be overlapped, and that the arrangement of the positioning blades may be modified accordingly.

When the positioning blades are arranged in marginally overlapped relation, as represented in Figs. 10 and 14, the alternate upper forming ribs 26 are preferably made slightly deeper than the intermediate ribs, as represented in Fig. 5, in order to provide the requisite fullness in the material intermediate the pairs of standing tucks for formation of the lateral folds formed beneath similar and oppositely directed adjacent lateral folds of the adjacent group or pair of standing tucks.

By reference to the drawings, it will be observed that at opposite ends of the series the shanks 44 are provided only with the inwardly extending blades 43', an oppositely extending portion being obviously unnecessary at the end of the series.

From the foregoing description it will be observed that, while the present improvement is especially designed for production of mushroom tucking of a particular type, it is susceptible of easy modification for other kinds of tucking, and certain of its distinctive features are adapted for use independently of others within the scope of the present invention. It will of course be understood that the several forming and positioning elements may be so arranged as to produce the different styles of tucking represented in my said Patent No. 1,164,790.

Having thus set forth the nature of the invention, what I claim herein is:—

1. A tucking device comprising a series of spaced and similarly directed forming elements, similarly directed positioning elements extending laterally intermediate and beneath adjacent groups of forming elements of said series, and creasing elements

also similarly directed and disposed intermediate adjacent elements of said groups of forming elements and above said positioning elements.

5 2. A tucking device comprising a series of spaced and similarly directed forming blades, similarly directed positioning blades extending laterally intermediate and beneath adjacent groups of forming blades of said 10 series, the adjacent positioning blades being disposed in marginally overlapping and spaced relation, and creasing blades also similarly directed and disposed intermediate adjacent blades of said groups of forming 15 blades and above the overlapped margins of the positioning blades.

3. A tucking device comprising a series of spaced and similarly directed forming blades, similarly directed positioning blades 20 extending laterally intermediate and beneath adjacent groups of forming blades of said series and terminating rearward of the delivery extremities of the latter, and creasing blades also similarly directed and 25 disposed above said positioning blades and intermediate adjacent blades of said groups of forming blades and terminating rearward of the extremities of the latter.

4. A tucking device comprising a series of 30 spaced and similarly directed forming blades, similarly directed positioning blades extending laterally intermediate and beneath adjacent groups of forming blades of said series and each having a supporting shank 35 extending intermediate said groups, and similarly directed creasing blades disposed at opposite sides of said shanks and overhanging and disposed in angular relation with the marginal portions of said positioning blades.

5. In combination, stitch-forming mechanism including a plurality of laterally spaced reciprocating needles, means for producing in a body fabric a plurality of standing tucks in groups each having component tucks directed to opposite sides of a needle, and laterally extending positioning blades with their opposite edges engaging and adapted to direct the body fabric at the 50 bases of tucks of adjacent groups respectively beneath adjacent needles.

6. In combination, stitch-forming mechanism including a plurality of laterally spaced reciprocating needles, means for producing in a body fabric a plurality of standing tucks in groups each having component tucks directed to opposite sides of a needle, and laterally extending positioning blades with the margin of each in overlapping 60 relation with that of an adjacent blade and adapted to engage and direct the body fabric at the bases of tucks of adjacent groups respectively beneath adjacent needles.

7. The combination with stitch-forming 65 mechanism including a reciprocating needle,

and feeding mechanism, of a tucking device comprising tuck-forming elements having their delivery ends directed wholly to opposite sides of the needle-path and extending in the direction of feed, and an intermediate 70 creasing element directed toward the needle-path.

8. The combination with stitch-forming mechanism including a reciprocating needle, and feeding mechanism, of a tucking device 75 comprising tuck-forming blades having their delivery end portions directed in substantial parallelism wholly to opposite sides of the needle-path and within the direction of feed, and an intermediate creasing blade 80 directed toward and disposed in advance of the needle-path.

9. The combination with stitch-forming mechanism including a plurality of reciprocating needles, and feeding mechanism, of a 85 tucking device comprising a series of substantially parallel tuck-forming blades extending in the direction of feed and arranged in groups each containing blades at opposite sides of a needle-path, similarly 90 directed positioning blades extending intermediate adjacent groups and beneath component forming elements thereof, and creasing blades also directed within the line of feed and disposed intermediate the component 95 blades of said groups and in alinement with their respective needles.

10. The combination with stitch-forming mechanism including a plurality of reciprocating needles, and feeding mechanism, of a 100 tucking device comprising a series of substantially parallel tuck-forming blades extending in the direction of feed and arranged in groups each containing blades at opposite sides of a needle-path, and similarly 105 directed positioning blades extending intermediate adjacent groups and beneath component forming elements thereof and laterally beyond the paths of movement of the needles of the respective groups of forming 110 blades.

11. The combination with stitch-forming mechanism including a plurality of reciprocating needles, feeding mechanism and a presser-foot having an operative face formed 115 with a series of parallel grooves extending each toward a needle-path and in the direction of feed, of a series of standing tuck-forming blades arranged in pairs each having its component blades in register with a 120 groove of said presser-foot, and creasing blades each disposed intermediate and directed parallel with the component blades of a pair and toward the respective needle-path.

12. The combination with stitch-forming mechanism including a plurality of reciprocating needles, feeding mechanism and a presser-foot having an operative face formed with a series of parallel grooves extending 125 130

each toward a needle-path and in the direction of feed and having flaring mouths adjacent the needle-paths, of a series of standing tuck-forming blades arranged in pairs 5 each having its component blades extended within the flaring mouth of one of said presser-foot grooves, and creasing blades each disposed intermediate and directed parallel with the component blades of a pair 10 and toward the respective needle-path.

13. The combination with stitch-forming mechanism including a plurality of reciprocating needles, and feeding mechanism, of a tucking device comprising a series of 15 spaced and similarly directed forming blades sustained in fixed position and arranged in pairs of each of which the component blades are directed to opposite sides of a needle-path, and a plurality of yieldingly sustained 20 creasing blades each interposed between the component blades of a pair of forming blades and directed toward its respective needle-path.

14. The combination with stitch-forming mechanism including a plurality of reciprocating needles, a presser-foot and a presser-bar sustaining the same, of a tucking device comprising a series of spaced and similarly directed forming blades sustained in 25 fixed position and arranged in pairs of each of which the component blades are directed to opposite sides of a needle-path, and a plurality of creasing blades sustained by said presser-bar and each interposed between the 30 component blades of a pair of forming blades and directed toward its respective needle-path.

15. The combination with stitch-forming mechanism including a plurality of reciprocating needles, a presser-foot and a presser-bar sustaining the same, of a tucking device comprising a series of spaced and similarly directed forming blades sustained in fixed 40 position and arranged in pairs of each of which the component blades are directed to opposite sides of a needle-path, a plurality of creasing blades each interposed between the component blades of a pair of forming blades and arranged in front of and directed 45 toward its respective needle-path, and a carrier 50 for said creasing blades embracing the several needle-paths.

16. In a sewing machine, the combination with the frame comprising a bed-plate and an overhanging bracket-arm, and stitch-forming and feeding mechanisms, of a tucking device comprising a forming member sustained by the bed-plate and comprising 55 a series of convergent standing tuck-form-

ing elements of progressively decreasing 60 width and increasing height merging at their delivery end portions in substantially parallel standing blades extending in the direction of feed, and a superposed forming member movably sustained from the bracket-arm and comprising a depending series of convergent forming elements rigidly connected together at their ends and unconnected intermediate their ends to expose the intervening spaces, said depending elements 70 extending intermediate the standing forming elements of the lower member.

17. In a sewing machine, the combination with the frame comprising a bed-plate and an overhanging bracket-arm, and stitch-forming and feeding mechanisms, of a tucking device comprising a forming plate sustained by the bed-plate and formed with a series of convergent tuck-forming ribs of 75 progressively decreasing width and increasing height merging at their delivery end portions in substantially parallel standing blades extending in the direction of feed, and a superposed forming plate movably sustained from the bracket-arm and comprising a depending series of convergent forming ribs normally entering the spaces between the lower forming ribs, said plate being formed in its contracted portion with 80 an inspection aperture through which access 85 may be had between the upper forming ribs to the lower forming ribs.

18. The combination with stitch-forming mechanism including a reciprocating needle, and feeding mechanism, of a tucking device 95 comprising tuck-forming elements disposed at opposite sides of the line of seam formation and extending in the direction of feed, an intermediate creasing element disposed in the line of seam formation, and means for 100 deflecting the bases of the tucks formed by the tuck-forming elements within the line of seam formation.

19. The combination with stitch-forming mechanism including a plurality of reciprocating needles, and feeding mechanism, of a tucking device comprising a pair of tuck-forming elements for each needle, the tuck-forming elements of each pair being disposed respectively at opposite sides of each 105 line of stitching and a plurality of creasing elements directed toward the needle-paths, each of said creasing elements being disposed intermediate a pair of tuck-forming elements.

In testimony whereof, I have signed my name to this specification.

ALBERT H. DE VOE.
